FIGURE 1 is a side elevational view of a fishhook disgorger showing my new design;

FIGURE 2 is an end elevational view thereof, looking to the right in FIGURE 1;

FIGURE 3 is an end elevational view thereof, looking to the left in FIGURE 1;

FIGURE 4 is a top plan view thereof; and

FIGURE 5 is a bottom plan view thereof.

The characteristic feature of my design resides in the specific configuration of the handle member in association with the elongated shank portion as best illustrated in FIGURE 1.

I claim:

The ornamental design for a fishhook disgorger, as shown and described.
